UNITED STATES PATENT OFFICE.

JACOB WILLIAM LATTIG, OF EASTON, PENNSYLVANIA.

ELECTRIC SIGNALING APPARATUS AND SYSTEM FOR RAILWAYS.

SPECIFICATION forming part of Letters Patent No. 499,126, dated June 6, 1893.

Application filed February 21, 1893. Serial No. 463,199. (No model.)

To all whom it may concern:

Be it known that I, JACOB WILLIAM LATTIG, of Easton, in the county of Northampton and State of Pennsylvania, have invented certain 5 new and useful Improvements in Electric Signaling Apparatus and Systems for Railways, of which the following is a specification.

My present invention is directed to an automatic block system of danger or home and 10 caution or distant signals similar to that described in my application for Letters Patent, Serial No. 456,380, filed December 27, 1892; and like the latter contemplates the employment of an electric motor for actuating the signal 15 operating mechanism to move the signal to safety.

The particular form of electric motor which I here describe in illustration of my invention is a solenoid or sucking magnet, to the core 20 or cores of which the signal actuating rod is connected.

The nature of my improvements can best be explained and understood by reference to the accompanying drawings, in which—

25 Figure 1 is a representation—in part diagrammatic—of an automatic block system of danger and caution signals involving my invention. Fig. 2 is an enlarged view of the solenoid employed by me. Figs. 3, 4 and 5 30 are diagrammatic representations of modified circuit arrangements.

To illustrate the system I represent two insulated blocks or railway track sections X', X², each provided with a signal pole carrying 35 two pivoted and counterweighted semaphore blades B, B', the one "home" the other "distant." For operating each blade there is a solenoid C, having its core or cores connected by a rod a to the weighted end of the blade—40 the arrangement being such that when the solenoid is energized its core will be drawn up, thus lifting the rod a and moving the signal to safety. At a suitable point on each rod a is interposed a short link a', to permit 45 the armature or core to move up and down in a right line, notwithstanding the slight lateral movement of the upper portion of the rod a in rising and falling due to its connection to the pivoted semaphore blade. Each solenoid 50 has its spools connected at the top to an angle piece c preferably of non-magnetic material, the vertical limb of which is bolted to

the signal pole. The magnetic yoke for the spools is shown at d. It is placed on top of the horizontal limb of the angle piece c, and is provided with short cores d' which extend through the angle piece, into the interior of the spools. The yoke is held in place by bolts e which pass down loosely through the yoke and screw into or are otherwise fastened to 60 the angle piece. Encircling the bolts, and interposed between the heads of the latter and the yoke d, are springs f. The object of this is to furnish a cushion or yielding and elastic buffer for the cores to bring up against, when 65 they are drawn up. Other forms of elastic cushion may be employed but I prefer the one just described for the reason that when the armature cores are in contact with the cores d' of the yoke, there will be a closed 70 magnetic circuit—which is particularly adapted for tractive power. Thus, after the signal has been pulled to safety, the current in the solenoid may be greatly reduced, and still serve to maintain the signal in that position. 75

To the operating rod a of the danger signal B is connected a lever b pivoted to a casting g secured to the pole. A like lever is connected to the rod a of the caution signal; but this lever has no part in the electrical functioning of the apparatus. The upper or danger signal lever b however is by a pin and slot connection joined to a vertical rod h which is arranged to slide up and down in guides on the casting g, and has on it two insulated contacts m', n', which operate the one in connection with the fixed contacts m, the other in connection with the fixed contacts n. In the path of each armature is the movable member o of a switch which plays between two 85 contacts p, p', with the lower one p of which it normally is in contact. In connection with each signal operating appliance there is a relay D, which controls two sets of contacts x, y, the one set insulated from the other. 90

The circuit arrangements are as follows: For the home signal—the relay D is included in a constantly closed track circuit 1 which is completed through the rails of the insulated track section or block appropriate to that signal; a second circuit 2—the signal operating circuit, includes the solenoid, and is completed through the contacts x, and o, p; a third circuit 3—which I will call the locking and re-

leasing circuit—is a shunt around the large battery of circuit 2, and is completed through the contacts y and o, p' . This last named circuit also includes the solenoid, and is supplied from a small battery of only enough power to energize the solenoid sufficiently to hold the cores in the position to which they are brought through the closure of circuit 2. There is the same system of circuits $1^x, 2^x, 3^x$, for the caution or distant signal, save that the primary circuit 1^x is a grounded circuit, of which the track forms no part, and is completed through two sets of contacts, viz: the contacts m, m' controlled by the home signal of the same section or block, and the contacts n, n' controlled by the home signal of the next block in advance. The mechanical connections are such that whenever and so long as a home signal stands at danger the contacts m, m' and n, n' controlled by it will be open.

In Fig. 1 a train, typified at Y , is supposed to have just left section X' and to be on section X^2 , traveling in the direction of the arrow. Consequently in section X' track circuit 1 is closed through relay D, the latter is energized and by attracting its armature has closed the contacts x, y . Signal operating circuit 2 has thereby been closed, with the result of causing the solenoid to draw up its armature, thus lowering the home signal to safety. The armature however by the time it has moved up far enough to set the signal to safety, has lifted the key o from contact p , thus breaking the signal operating circuit 2, and has brought it into contact with contact p' , thus completing the locking and releasing circuit 3, by which the solenoid is energized just enough to hold its armature in place. By this movement the contacts m, m' and n, n' , controlled by the home signal B have been closed. The caution or distant signal B' however of section X' still remains at danger, because while the contacts m, m' of its circuit 1 are closed, the contacts n, n' of that circuit controlled by the home signal of section X^2 still remain open, this being due to the fact that as the train Y is still on section X^2 , the track circuit 1 of that section is completed through the path of lower resistance offered by the wheels and axles of the train, thus cutting out the relay magnet D of section X^2 , and consequently putting both of its signals to danger. As soon however as the train Y passes beyond section X^2 , the signals in that section will stand as now represented for section X' , while in section X' the caution signal will go to safety.

In Figs. 3, 4 and 5 are shown different circuit arrangements which may be used as substitutes for the particular arrangement of circuit 3, (the locking and releasing circuit) shown in Fig. 1—all of these arrangements having a common object viz: to cut down, after the signal has been brought to safety, the battery power from that required to bring the signal to that position to that requisite to hold it in that position. In Fig. 4 for exam-

ple, the shunt 3 is connected to only such part of the battery of circuit 2, as needed to hold the signal at safety and relay D has but one set of contacts x . In Fig. 3, the upper contact p' is dispensed with and the circuit 3 is completed through a constantly closed shunt 3 around the contacts o, p , containing a resistance R, which will permit the passage of only current enough to cause the solenoid to hold its armature at safety. Relay D in this instance also has only one set of contacts x . In Fig. 5, the relay D as before controls only one set of contacts x . But in this figure, the circuit arrangements differ from any shown in the preceding figures in that the solenoid is cut out as soon as it has done its work, and an electro magnetically controlled detent or lock is relied on to hold the signal in the safety position to which the solenoid has brought it. To this end the locking and releasing circuit 3 is in a shunt from the main operating circuit 2, around the solenoid, and is completed through the upper contact p' ; and if it includes a locking and releasing magnet E, and a resistance R so proportioned as to permit the passage of only current enough to energize properly the magnet E. The magnet E is mounted in a box F secured to the signal pole, in the line of the signal operating rod a, which passes through the box as shown. Pivoted to the box is the armature lever E' of the magnet E, which lever on its face next to the rod a carries a miter-shaped nose or dog i, which, when the rod is in the position which it occupies when the signal is at safety, registers with a like shaped notch j on the rod a. Under this arrangement when the circuit 2 is closed, the solenoid will bring the signal to safety, through the movement of its armature. By the time the signal is at safety the armature in rising will have lifted the key o from p into contact with p' thus cutting out the solenoid and at the same time closing the shunt 3 around the latter, whereby the locking and releasing magnet E is energized and by attracting its armature lever locks the rod a in place by the engagement of the dog i and the notch j. This condition of affairs will continue until the circuit is broken at x, when the magnet E will release its armature and the signal consequently will at once rise to danger.

It will of course be understood that the circuits represented in Figs. 3, 4, 5 are applicable as well to the distant signal as to the home signal.

Having now described my improvements and the manner in which the same are or may be carried into effect, what I claim herein as new and of my own invention is—

1. The combination of a series of home or danger signals B; a series of circuits 1, 2, 3, for each home signal; a relay D in each circuit 1 controlling contacts in the other circuits; a solenoid in each circuit 2, having its armature core or cores connected to and adapted to operate the home signal; a series

of caution or distant signals B', a series of circuits 1^x, 2^x, 3^x, for each distant signal; two sets of contacts m, m' and n, n', in each circuit 1^x controlled the one by the home signal mechanism of the same section, the other by the home signal mechanism of the section next in advance; a solenoid in each circuit 2^x having its armature core or cores connected to and adapted to operate the caution or distant signal; and a contact controlled by the moving part of each solenoid (pertaining to both the home and the distant signal mechanism) for successively completing each circuit 2, 3, or 2^x, 3^x, appropriate to its signal, all as hereinbefore specified.

2. The combination of the signal, the solenoid and its armature core or cores connected to and adapted to operate the signal; the signal operating circuit including the solenoid, and completed through contacts o, p; the signal locking and releasing circuit completed through contacts o, p' and containing the lock-

ing and releasing magnet E; the armature lever E' connected to a dog adapted to engage the signal operating rod; and the primary circuit including the relay D and controlling contacts through which the signal operating and locking and releasing circuits are completed—under the arrangement and for joint operation as hereinbefore set forth.

3. The combination of the signal, the solenoid having its armature cores connected to and adapted to operate the signal, and provided with a spring yielding yoke with cores entering the spools of the solenoid to constitute an elastic buffer for the armature cores, substantially as and for the purposes hereinbefore set forth.

In testimony whereof I affix my signature in presence of two witnesses.

JACOB WILLIAM LATTIG.
